JEROME SANDIN, OF PENN TOWNSHIP, ALLEGHENY COUNTY, AND HERBERT J. CRABBS, OF IRWIN, PENNSYLVANIA, ASSIGNORS TO WESTINGHOUSE ELECTRIC AND MANUFACTURING COMPANY, A CORPORATION OF PENNSYLVANIA.

SWITCH.

Application filed April 12, 1927. Serial No. 183,126.

Our invention relates to switches and particularly to switches of the type known as disconnecting switches.

Switches of this class are generally employed for interrupting the currents flowing in a transmission line at power houses, substations and transformer towers along the line. Such switches are usually of the air-break type and are inexpensive to manufacture, rugged in construction and are in demand for outdoor installations, particularly where oil circuit breakers would be impractical.

The most desirable construction for a switch of this type for certain installations generally comprises a base member having spaced insulators disposed therein for supporting terminal members. The terminal members are usually electrically connected in the closed position of the switch by a flexible shunt carried by a mechanism which is adapted to move one end of the shunt and thereby make or break the electrical connection between the terminals.

Heretofore, it has been the general practice to provide links for supporting the flexible shunt, the latter being wound around, or permitted to rest upon, the supporting links. This construction is undesirable since the flexible shunt is so constrained by contact with the links, as to be bent sharply in a great number of places and also because of the abrasion to which the shunt is obviously subjected. The shunt is materially impaired and its life greatly shortened.

It is an object of our invention to provide a disconnecting switch of the above type having means associated with the shunt-supporting mechanism for predetermining the position of the shunt eliminating sharp bends therein and maintaining it clear of the other members of the switch mechanism at all times.

Another object of our invention is to provide a disconnecting switch of the same type having means for supporting the shunt substantially in the plane of the movement of the shunt support and one that shall maintain the shunt clear of all members of the switch mechanism.

These and other objects that may be made apparent throughout the further description of our invention are attained by the appa-

ratus hereinafter described, and illustrated in the accompanying drawing, wherein,

Figure 1 is an enlarged detail view of one of the parts included in a switch mechanism embodying our invention.

Fig. 2 is a side view of the part shown in Fig. 1, and

Fig. 3 is a side view, in elevation, of a switch mechanism embodying our invention.

In practicing our invention, we provide a switch mechanism comprising a base 11, a pair of spaced insulators 12 and 13 disposed on the base, terminal members 14 and 15 carried by the respective insulators 12 and 13, an insulator 16 movably mounted, as indicated at 17, a movable switch member 18 carried by the insulators 12 and 16 adapted to engage switch jaws 19 disposed on the terminal member 15, a flexible shunt 21 for electrically connecting the terminal member 14 to the switch member 18 and means 22 cooperating with the movable switch member for supporting, and predetermining the position of, the shunt 21.

Referring to the drawings, the movable switch member 18 comprises a contact member 20 for engaging the switch jaws 19, a pair of links 23 and 24 connected at their adjacent ends by a pivot 25. The other ends of the links 23 and 24 are pivotally connected to the terminal member 14, and contact member 20 respectively by means of pivots 26 and 27.

The shunt-supporting means 22 comprises an arcuate resilient member 29 fastened to the pivot 25 adjacent its center by any suitable means, such as clamp 31 shown in Fig. 1. The ends of the member 29 are fastened to the shunt 21 by means of bolts 32.

Fig. 3 shows the switch mechanism in its closed position, as illustrated by the solid lines, and in its open position, as illustrated by the broken lines.

The shunt 21 is connected to the terminal member 14 by any suitable means, such as the screws 33, and to the contact member 20 by the screws 34. Clamps 35 are provided at certain points for rendering the shunt more rigid and aligning a plurality of shunt members which may be employed where a single shunt would be inadequate in current-carrying capacity, in a predetermined space relation, and also, in cases where the shunt 21 is of sufficient length to require additional sup-

ports, members 38 and 39 may be provided for cooperating with the links 23 and 24 and the shunt 21 for holding the shunt more rigidly in place.

5 The movable contact member 20 is mounted on the insulator 16 by means of a pivot 36 and is adapted to turn thereon to a predetermined extent when necessary upon separation of the contact member 20 from the 10 switch jaws 19 for the purpose of breaking any corrosive seal that may form upon the contact jaws.

A stop member 37 is provided on the insulator 16 for cooperating with the pivot 27 15 to limit the movement of the contact member 20.

Referring to Fig. 3, when the switch is being opened the contact member 20 turns on the pivot 36 in a clockwise direction until the 20 pivot 27 comes into engagement with the stop 37. Thereafter, the stop 37 and the pivots 27 and 36 cooperate to hold the contact 20 relative to the insulator 16, until disengagement of the contact member 20 from the switch 25 jaws 19 is completed. Arcing horns 40 are provided on the contact member 20 and switch jaws 19 for their protection, which is the usual practice in switch mechanism of this type.

30 Accordingly, we have devised a disconnecting switch comprising a flexible shunt for electrically connecting its terminals and a support for the shunt carried by the switch mechanism and arranged to support the shunt at a plurality of spaced positions, whereby 35 it is maintained clear of the path of the movement of all parts of the switch mechanism.

40 While we have illustrated and described only one embodiment of our invention, it will be apparent to those skilled in the art that certain changes, modifications, substitutions, additions and omissions may be made in the switch mechanism above described without 45 departing from the spirit and scope of the appended claims.

We claim as our invention:

1. Switch mechanism comprising switch 50 jaws, a movable contact member for engaging the switch jaws, a fixed terminal member, a flexible shunt connecting the fixed terminal to the movable contact member and means comprising a linkage pivotally connected to the fixed terminal member and the movable

contact member and a support pivoted to the 55 linkage for supporting the flexible shunt in such manner as to prevent sharp bends therein.

2. Switch mechanism comprising switch jaws, a movable contact member for engaging 60 the switch jaws, a fixed terminal member, a flexible shunt connecting the fixed terminal to the movable contact member and means for supporting the shunt substantially in the plane of movement of the movable contact 65 member and clear of all of the said members comprising a pair of hinged links and a support connected adjacent its ends to the shunt, and pivotally connected intermediate its ends to the said links.

70 3. The combination with a disconnecting switch having fixed contact jaws, a movable contact member for engaging the contact jaws, a fixed terminal member, a flexible shunt connecting the fixed terminal and the contact 75 member and a folding support for the shunt, of a means carried by the folding support comprising links pivotally connected to the support for supporting the flexible shunt at a plurality of spaced points, whereby the 80 flexible shunt is maintained clear of the folding support.

4. A switch mechanism comprising a base, a pair of spaced terminals, a switch blade having two parts, the contiguous ends of the 85 two parts being pivotally connected together, a flexible shunt for electrically connecting the remote ends of the switch blade having a resilient member disposed on the center-pivot portion thereof for supporting the flexible 90 shunt free from the blade.

5. In a switch mechanism comprising a base member, a pair of spaced terminals, and a flexible conductor for electrically connecting the terminals, a support for the conductor comprising two members pivotally connected together and pivotally supported at one end adjacent one of the said terminal members, a movable insulator for supporting the other end and a resilient member for cooperating with the said support and the flexible conductor for maintaining spaced relation to the said support.

100 In testimony whereof, we have hereunto 105 subscribed our names this 8th day of April, 1927.

JEROME SANDIN.
HERBERT J. CRABBS.
